UNITED STATES PATENT OFFICE.

GEORGE W. WALLIN, OF McCOOL JUNCTION, NEBRASKA.

MAIL-CATCHER.

1,002,885.

Specification of Letters Patent. Patented Sept. 12, 1911.

Application filed June 10, 1911. Serial No. 632,470.

To all whom it may concern:

Be it known that I, GEORGE W. WALLIN, a citizen of the United States, and a resident of McCool Junction, in the county of York 5 and State of Nebraska, have invented certain new and useful Improvements in Mail-Catchers, of which the following is a specification, reference being had to the accompanying drawings.

10 This invention has relation to an improved catcher employed in connection with a mail car; and the object of my invention is to provide a device of this general character of a simple and inexpensive nature 15 and of a durable construction which shall be capable of convenient and accurate adjustment in position within a car door frame, to catch and hold a mail bag, suspended from a suitable crane.

20 With these and other objects in view, the present invention consists in the combination and arrangement of parts as will be hereinafter more fully described and finally pointed out in the appended claims, it being further understood that changes in the 25 specific structure shown and described may be made within the scope of the claims, without departing from the spirit of the invention.

30 In the accompanying drawings forming a part of this specification, and in which like numerals of reference indicate similar parts in the several views; Figure 1, shows a broken portion of a mail car disclosing 35 my catcher in position to catch a suspended mail pouch. Fig. 2, shows a top view of the catcher disclosing the same in an open position to receive the pouch. Fig. 3, is a top view showing the instrumentalities in a 40 closed or clasping position in dotted lines. Fig. 4, is an elevational view with portions broken away of my mail catcher. Fig. 5, shows the front view of the catcher with the clasping arms in an open position. Fig. 45 6, shows an enlarged fragmentary detail of the link disclosing the collar with the bar dividing the same into two equal sections, and Figs. 7 and 8, show detail views of the two clasping members as detached.

50 In the accompanying drawings the letter A, designates a fragmentary portion of a mail car provided with the door frame B. This door frame at two suitable opposite points is provided with the bearings 2, arranged to pivotally hold the rock shaft 1, having the stop shoulders 3. Secured to

this rock shaft 1, as shown in Fig. 2, is the lever 4, having the boss 5, to receive the shaft 1. This lever at one end is provided with the handle 5', while secured near the outer end of the lever 4, as shown in Figs. 4 and 5, is the striding head 6, which is secured to the lever 4 through the intermediate of the square block 7, a set screw 8, passing through this head and block so that this head is adjustably secured to the lever 4. The striding head 6, is provided with an aperture through which extends the stud 9, this stud being provided with the guide shoulder 10, and carrying the washer plate 11, held to the stud by means of the nut 12.

Firmly secured to the striding head 6, is an oblong base plate 13, which has the downward extending flange 14, along its forward edge, while to the rear I provide 75 two counterpart stop ears 15, which curve upwardly and forwardly and are held in spaced relation, as shown in Figs. 2 and 3. Pivoted to the stud 9, are two equiformed bars each including an apertured ear 16, for engagement with the stud 9, and extending from each ear 16, in one direction is a pouch clasping arm 17, each arm terminating in a reversely curved end 18, while a curved tang 20, extends from each 85 ear in an opposite direction. As shown in Figs. 2 and 3, these tangs 20, are curved laterally outward in opposite directions.

Slidably held upon the stud 9, and in engagement with the guide shoulder 10, is the 90 link 22, which at its forward end carries the resilient bowed yoke 23, which encompasses the clasping arms 17, as shown in Fig. 3. At the end opposite the yoke 23, the link is provided with the collar 25, which is divided into two sections by means of the spanner bar 26, secured to the link collar by means of the rivet 19, as shown in Fig. 6, and dividing the collar into two sections. As shown in the drawings, the tangs 20, extend through the collar 25, curving in opposite directions.

The operation of my device is very simple. When it is intended to clasp and catch the mail pouch, the lever 4, is swung in a horizontal position so that the arms 17, will clasp the mail pouch intermediate of its ends. In Fig. 1, a mail pouch D, is shown, suspended in the usual manner from a crane E. As shown, the pouch is squarely in the 110 path of the catcher when the lever 4, is held in a horizontal position. In adjusting the

instrumentalities to receive a pouch, the operator draws the yoke 23, forward which results in the bar 26, of the divided collar 25, forcing the tangs 20, outward, so that 5 the two clasping members 17, are finally held in a stopped position within and against the ears 15, as shown in Fig. 3. In this position of the catcher, the resilient yoke 23, is positioned near the forward ends 10 of the bowed clasping arms 17. Now on coming into contact with the mail pouch, the shock of the impact is partly taken up by the curved resilient bowed yoke 23, which at the same time flies back, and in its retro- 15 grade movement the collar 25, actuates the tangs 20, to close the arms, to firmly clasp the pouch, the rearward movement of the link being stopped by the shoulder 10, coming into contact with the forward end of 20 the link, as will be understood in referring to Fig. 3, where the closed position of the arms is shown. The spread of the arms 17, is limited by the stop arms 15. The collar 25, operates as a detent to hold the arms 25 in a clasped position. The bag once having been clasped, is firmly held between the arms and cannot become casually detached. The mail pouch is finally released in clasping 30 the yoke and drawing the same forward, which results in the pouch being shoved outward while the arms are spread.

A mail catcher constructed according to my invention is simple and inexpensive and both durable and efficient in operation, and 35 may be easily adjusted between the door frame of a mail car. So also could the mail catcher be held stationary while the pouch would be suspended from a moving car, to serve in delivering a mail pouch from a 40 moving car to a stationary crane.

Having thus described my said invention, what I claim as new and desire to secure by United States Letters Patent is:—

1. A mail bag catcher having in combination, a rock shaft, a lever secured to said rock shaft, a striding head adjustably secured to said lever, an oblong base plate secured to said head having a downwardly extending forward flange and two rear-

wardly positioned upwardly and forwardly 50 curved spaced stop ears, a stud secured centrally to said base between said ears having a guide shoulder, two equiformed bars pivotally held to said stud, each comprising an apertured ear for engagement with said 55 stud from which extends in one direction a bowed clasping arm terminating in a re- versely curved end, a curved tang extending from each ear in an opposite direction, said tangs being curved laterally outward, 60 and a link slidably held upon said shoulder having a resilient bowed yoke at one end encompassing said clasping arms and at the other being provided with a divided collar said tangs extending through said 65 collar, said stop ears limiting the spread of said arms.

2. A mail bag catcher having in combination, a rock shaft, a lever secured to said rock shaft, a striding head adjustably secured to said lever, an oblong base plate secured to said head having a downwardly extending forward flange and two rear- 70 wardly positioned upwardly and forwardly 75 curved spaced stop ears, a stud secured centrally to said base between said ears having a guide shoulder, two equiformed bars pivotally held to said stud, each comprising an apertured ear for engagement with said stud from which extends in one direction a 80 bowed clasping arm terminating in a re- versely curved end, a curved tang extending from each ear in an opposite direction, said tangs being curved laterally outward, a link 85 slidably held upon said shoulder having a resilient bowed yoke at one end encompassing said clasping arms and at the other being provided with a divided collar said tangs extending through said collar, said stop ears limiting the spread of said arms, 90 and means to slidably hold said link to said stud.

In testimony whereof I affix my signature, in presence of two witnesses.

GEORGE W. WALLIN.
